DESIGN FOR A TEXTILE FABRIC

Thomas F. Gurry, Jr., Port Washington, N. Y.

Application March 24, 1941, Serial No. 99,793

Term of patent 3½ years

To all whom it may concern:

Be it known that I, Thomas F. Gurry, Jr., a citizen of the United States, residing at Port Washington, Long Island, in the county of Nassau and State of New York, have invented a new, original, and ornamental Design for a Textile Fabric, of which the following is a specification, reference being had to the accompanying drawing, forming part thereof, wherein the figure is a plan view of a textile fabric showing my new design.

I claim:

The ornamental design for a textile fabric, substantially as shown.
